COMBINED VAPORIZER AND ECONOMIZER FOR INTERNAL COMBUSTION ENGINES

Original Filed Nov. 18, 1926 2 Sheets-Sheet 2

UNITED STATES PATENT OFFICE

WILLIAM EDGAR STANAWAY, OF KASLO, BRITISH COLUMBIA, CANADA, ASSIGNOR OF ONE-FOURTH TO HOWARD DAY DAWSON AND ONE-FOURTH TO WILLIAM VIDLER PAPWORTH, BOTH OF KASLO, CANADA, AND ONE-EIGHTH TO ALEXANDER GRANT, OF WHITEWATER MINE, NEAR RETALLACK STATION, CANADA, AND ONE-EIGHTH TO DONALD GRANT, OF AINSWORTH, CANADA

COMBINED VAPORIZER AND ECONOMIZER FOR INTERNAL-COMBUSTION ENGINES

Application filed November 18, 1926, Serial No. 149,199. Renewed December 19, 1930.

This invention relates to improvements in a combined vaporizer and economizer for internal combustion engines, and the objects of the invention are to provide a simply constructed, light and durable means for starting internal combustion engines and at the same time eliminate the necessity of choking the carburetor while minimizing the dilution of the lubrication oils by vaporizing the liquid fuel and mixing the same with air, so that when introduced into the engine manifold, the mixture with more air coming free through the carburetor provides an explosive mixture for starting the engine.

In carrying out my invention, I provide a vaporizing chamber in which the primary mixture for starting the engine is mixed, and then introduced directly into the engine manifold without passing through the carburetor.

Further objects are to provide a device of this description that may be used as a gas saver when the engine is running.

With the foregoing and other objects in view and hereinafter more fully referred to, the invention comprises in combination with an internal combustion engine, a vaporizing chamber provided with a heating element, a pair of conduits provided with three-way valves communicating with the vaporizing chamber, a liquid fuel container communicating with one of the conduits and means operable from the driver's seat for operating the valves.

Referring now to the drawings in which like characters of reference indicate corresponding parts in each figure

Figure 1 is a longitudinal section of the apparatus as a whole.

Figure 2 is a section on the lines 2—2 of Figure 1.

Figure 3 is a plan view of the perforated disc.

Figure 4 is a side elevation partly in section of the dash control in gas saving position.

Figure 5 is an end view of Figure 4.

Figure 6 is an end view of Figure 4 when used as a vaporizer and choke eliminator.

Figure 7 is a plan view of the plunger for the gas saving valve.

Figure 8 is a side elevation of a modified form of vaporizing device.

Figure 9 is a diagrammatic view of the electric circuit.

Figure 10 is a diagrammatic showing of the connection with the engine.

Referring more particularly to the drawings in which a preferred form of my invention is illustrated and having reference in the first instance to the vaporizing chamber, this is designated by the numeral 10 and consists

of a length of tube, of metal or any other suitable material, and of suitable dimensions to meet the requirements of variously powered engines. Fixed to the ends of the vaporizing chamber are caps or plugs 11 and 12, the cap

or plug 11 on the lower end being provided with a stem 13 extending therethrough and suitably insulated as at 14.

The outer end of this stem is provided with a terminal 15 to which is attached a lead wire 16 from any suitable source of electric supply such as a battery (not shown).

On the inner end of the stem 13 are securing nuts, a washer and a perforated disc 17, (see Figure 3) adapted to engage with and retain the ends of the heating

elements 18 at the inner terminal. The other ends of these elements extend inside to the cap or plug 11 where they are grounded as

at 19 or in any suitable manner, and prevented from coming into contact with either the stem

13 or the chamber 10 by absorbent asbestos or the like 20. The circuit through the heater element 18 is closed or opened according to

the position of the dash control 21 of the three-way valves 22 and 23 comprising lever

25, plunger 38, bar 24 and disc 35 hereinafter more fully described and referred to. The

appliance is fixed in any suitable manner under the bonnet so that it can be readily

operated from the dash although in certain

makes of cars and on stationary or other internal combustion engines it may be necessary to fix the appliance in other positions.

Referring more particularly to Figure 4 it will be noted that the valve 22 is directly connected by means of a slotted bar or rod 24 having universal joint (not shown) when necessary and arranged in a suitable casing with the dial key member 25 so that a quarter turn by the dial key member 25 will operate the valve 22 in the same direction. When this key 25 is in the position as shown in Figures 4 and 5 and the plunger 38 is in the in position as shown in dotted lines in Figure 4 the valve 23 is automatically set in the position as shown in Figure 1, while the valve 22 will be in the position as indicated in dotted lines in Figure 1.

In other words the valve 23 will be open through the conduit 26 to the engine manifold and through the conduit 27 to the vaporizing chamber 10, while it will be closed to the conduit 28. The valve 22 at the same time will be open to the liquid fuel conduit 29 and to the liquid fuel container 30 through the conduit or pipe 31, the valve being closed at the same time to the conduit 32 communicating with the chamber 10 and protruding thereinto as at 33. A quarter turn of the bar 24 by the key 25 brings the valve 22 to the position indicated in full lines in Figure 1, closing the fuel supply conduit 29 and opening communication with the vaporizing chamber 10 and the liquid fuel container 30, being the position for using the device as a vaporizer and choke eliminator.

Mounted on the slotted bar 24 and held in place by a small key 34 fitted therein is a disc 35 adapted to turn with the bar on the latter being operated by the key 25. On this disc is fixed and insulated a switch part 36 wired direct to the engine battery so that when the disc 35 is revolved a quarter turn to the left, the switch part 36 engages with the switch part 37 fixed to the under side of the dash, (see Figure 6) and wired as at 16 to the terminal 15 of the vaporizing chamber 10, the grounding of the current being obtained through the engine, the circuit being now closed and the vaporizer in use.

Connected to the valve 23 is a plunger 38, when this plunger is pulled out the device is adapted to be used as a gas saver. When the plunger 38 is in the in position the valve 23 is set or positioned as indicated in Figure 1 in firm lines and by dotted lines in Figure 4 to operate the device as a vaporizer and choke eliminator. By pulling out the plunger 38 the valve 23 is set at the position indicated in full lines in Figure 4 causing the device to be used as a gas saver. The plunger 38 is provided with a lug 39 which is adapted to engage with the disc 35 limiting the travel on the plunger outwardly. On the outer end of the plunger is provided a

knob 40 to engage with the dial and thus limit the inward travel of the plunger. A notch 41 formed in the plunger 38 is designed to slidably engage with the disc 35 when the latter is turned.

The plunger 38 is provided with a slot 41 and the disc 35 with a slot 42 with which the plunger slidably engages and whereby, on the plunger being moved inwardly to operate the valve 23 to the position as shown in Figure 1, the slot 41 will register with the periphery of the disc 35 permitting the disc to be rotated through the key 25, see Figure 6.

When the plunger is pulled out the device automatically becomes a gas saver. In other words the plunger must be in to permit the key 25 to turn the disc. Furthermore the key 25 must be operated to turn the disc back to cut out position before it is possible to pull out the plunger.

The heating element and adsorbent material such as asbestos projects into the vaporizing chamber 10 sufficiently far to allow a reservoir for vaporized gas and air above and about the asbestos projections. The vaporized gas with the air drawn in through the valve 22 is then drawn through the valve 23 to the engine manifold when the engine is rotated for starting. The upper cap or plug 12 is bored to engage with two tubes 32 and 27 or the ends of two male three-way valves. The tube 32 is projecting downwardly into the vaporizing chamber 10 a suitable distance as at 33 to insure that no liquid fuel will be drawn through the tube 27 into the manifold. Attached to the tube 32 or screwed or inserted directly into the cap 12 in any well known manner, is a three-way valve 22, which in the position illustrated in Figure 1 cuts off the liquid supply 29 but allows that held in the container 30 to fall into the vaporizing chamber 10. This container in the case of engines fitted with vacuum tanks is left open to the air, the liquid fuel finding its own level and when allowed to drain into the vaporizing chamber does so by gravity and then air is also drawn through mixing with the vaporized fuel and when introduced into the engine manifold and mixed with more air coming in free through the carburetor forms the explosive mixture. In the case of engines fitted with force feed systems a simple valve and float would be required in the container 30. The container 30 may be a tube of larger dimensions than the tube 32 or may be of any suitable size and construction, and the amount of liquid fuel held therein may be varied to suit differently powered engines.

Coming now to the three-way valve 23 this is fixed to the tube 27 or screwed or inserted directly into the cap 12 and communicates with the gas tube 26 to the engine manifold and also to the tube 28 which is

open to the air and, as illustrated, suitably bent. When turned as shown in Figure 1, the valve 23 provides a clear passageway for the vaporized mixture from the vaporizing chamber 10 to the tube 26 and thence to the engine manifold, and when turned in another direction, as illustrated in Figure 4, closes the vaporizing chamber 10 and opens the air intake 28 permitting the engine to draw air direct through the tube 26. In this position my device is used as a gas saver.

In the foregoing description I have referred to the vaporizing chamber as disclosed in Figure 1, in a vertical position which would generally be the desirable position, but if found to be more suitable, this chamber can be used in a horizontal position as indicated in Figure 8. In this modified form liquid fuel and air would be introduced at one end, as at 43 whilst the vaporized fuel and air would be drawn from the other end 44. The general principle, however, is practically the same as already described.

In usual practice the liquid supply pipe 29 would be connected at a point just below the vacuum tank, whilst the vaporized mixture, after passing through the device, would be drawn into the engine manifold entirely independently of the carburetor, except that additional air is drawn through the carburetor to form the explosive mixture, the choke having been eliminated.

The device as previously referred to is preferably operated from the dash by means of a simple lever and dial switch as follows:— In one position with the lever and disk as in Figure 6 with the plunger 38 in, the valves 22 and 23 will be in the position illustrated in Figure 1, and in which the electrical circuit is closed and the device is in operation for starting the engine, the liquid fuel intake 29 being closed and the passageway 31 from the container 30 being open and the passageway 27 communicating directly through valve 23 with the pipe 26 leading to the engine manifold, while the air intake 28 is closed and the plunger 38 being locked in the in position. On the lever 25 being turned to the normal or cut out position as in Figure 5 to break or open the electrical circuit the valve 22 automatically assumes the position indicated by dotted lines in Figure 1, restoring communication between the fuel supply pipe 29 and the container 30 and closing the conduit 32 to the vaporizing chamber at the same time leaving the valve 23 in the normal position as shown in Figure 1.

My device may be fastened in any suitable position, preferably under the hood, also it may be secured on the dash or on the motor. In ordinary practice it would be placed below the liquid fuel supply so that the container 30 would be fed by gravity but in cases of necessity the device could be used with

force feed pumps and fitted with a simple valve and float.

The essential feature of my device is that the vaporized fuel mixture is drawn into the engine entirely independent of the carburetor while the choke may be entirely eliminated and consequently as the possibility of drawing liquid fuel into the engine is eliminated dilution of the lubricating oils will be in a great part reduced. Furthermore the device may be used as a gas saver by relieving the suction on the liquid fuel jet of the carburetor through the admittance of air to the manifold other than through the carburetor.

The circuit particularly illustrated in Figure 9 includes the battery 45, dial key including contacts 36 and 37, heating element 18 and ground 19.

As many changes could be made in the above construction and many apparently widely different embodiments of my invention, within the scope of the claims, constructed without departing from the spirit or scope thereof, it is intended that all matter contained in the accompanying specification and drawings shall be interpreted as illustrative and not in a limiting sense.

What I claim as my invention is:—

1. In a device of the character described and in combination with an internal combustion engine, a vaporizer having an electrical heating element therein, valves regulating the intake and discharge from the vaporizer, a plunger for one of said valves, a rotatably mounted rod for the other of said valves, a disc rigidly mounted on the rod and adapted to engage and disengage with the plunger on said rod being turned, a terminal on the disc and a terminal adjacent the disc whereby, on the rod being rotated, an electric circuit through the heating element is closed and opened simultaneously with the operation of opening and closing the fuel valve for the vaporizer.

2. A device of the character described and in combination with an internal combustion engine, a vaporizing chamber, a heating element for said chamber, valve controlled intake and discharge ports for the chamber, means for simultaneously operating the intake port valve and the heating element comprising a movably mounted rod operatively connected to said valve and provided with an operating key, a disc on said rod formed with engaging means therein, a terminal and a switch part associated with the disc whereby, on the rod being rotated to a predetermined point to open the intake port valve, an electric circuit for the heating element is simultaneously closed, co-operating plunger mechanism adapted in normal position to lock with the aforesaid means to retain the discharge port open, an air intake for said port normally retained closed whereby, on

the operating means for the intake port valve being returned to normal position the plunger mechanism is unlocked, and, on being operated, closes the discharge port and opens the air intake to supply air alone to the engine.

3. In a combined starting vaporizer and fuel economizer for internal combustion engines the combination of a vaporizing chamber, a fuel container, means for supplying liquid fuel to the vaporizing chamber, mechanism operable from without the chamber for simultaneously controlling the supply of liquid fuel to the chamber and the vaporizing means within the chamber, discharge means, an air intake associated with the said discharge means whereby the vaporized fuel is converted into a combustible mixture, mechanism for diverting the liquid supply and simultaneously cutting off the vaporizing means within the chamber and cooperating mechanism operable from without the chamber for closing the discharge means and simultaneously opening the air intake to supply air alone to the engine manifold.

4. In a combined starting vaporizer and fuel economizer for internal combustion engines the combination of a vaporizing chamber, a fuel container, means for supplying liquid fuel to the chamber, comprising an intake port communicating with the liquid fuel supply, the fuel container and the vaporizing chamber, mechanism operable from without the chamber for simultaneously controlling the supply of liquid fuel to the chamber and the vaporizing means within the chamber, discharge means comprising a discharge port communicating with the vaporizing chamber, the outer air and the engine manifold, the air intake associated with the discharge means serving to convert the vaporized fuel into a combustible mixture, three-way valves for each of the said intake and discharge ports, mechanism for diverting the liquid supply and simultaneously cutting off the vaporizing means within the chamber and cooperating mechanism operable from without the chamber for closing the discharge means and simultaneously opening the air intake to supply air alone to the engine manifold.

5. The invention according to claim 3 in which the vaporizing means within the chamber consist of an electrical heating element and an electric circuit for said element.

6. The invention according to claim 3 in which valve control means are provided to connect the fuel container with the fuel supply and with the vaporizing chamber, and an air vent for the container.

7. The invention according to claim 4 in which the cooperating mechanism for operating the discharge port valve comprises a plunger operatively connected to said valve and adapted in normal position to lock with

the intake port valve operating mechanism to retain the discharge port open and the air intake for the discharge port shut whereby, on the operating means for the intake port valve being returned to normal position, the plunger is unlocked and, on being pulled outwardly, closes the discharge port and opens the air intake.

In witness whereof I have hereunto set my hand.

WILLIAM EDGAR STANAWAY.
